The ornamental design for a hanger, as shown and described.

DESCRIPTION

FIG. 1 is a bottom perspective view of a hanger showing my new design.

FIG. 2 is a top perspective view thereof.

FIG. 3 is a front elevational view thereof.

FIG. 4 is a rear elevational view thereof.

FIG. 5 is a top plan view thereof.

FIG. 6 is a bottom plan view thereof.

FIG. 7 is a left side elevational view thereof.

FIG. 8 is a right side elevational view thereof; and,

FIG. 9 is a bottom perspective view of the hanger with the arms of the hanger folded.

The broken lines showing the hook of the hanger are for the purpose of illustrating unclaimed subject matter and form no part of the claimed design.
